CLARENCE C. SELDEN AND ROBERT D. PEARSON, OF LOS ANGELES, CALIFORNIA.

ART OF AND APPARATUS FOR THE TREATMENT OF PLANT FIBER OR THE LIKE.

Application filed October 15, 1925. Serial No. 62,578.

Our invention relates to an apparatus and art for treating plant fiber to increase the strength and life thereof, and to improve the finish of the fiber and the articles manufactured therefrom.

It is known that the cotton being charged with its natural oil by allowing it to remain in the pod on the plant, the cotton fibers will be considerably stronger in tension tests, breaking test, and will have a longer life and better finish than the cotton which must be harvested before being fully mature, or such cotton which is naturally dry by being grown in a very dry climate under irrigation, or without irrigation, conditions, and therefore it will be seen that the said dry cotton should be processed with its natural or substitute oil, or other vapors to establish the desired breaking test.

The object of our invention is to provide an apparatus and for treating plant fiber and more particularly cotton fiber, by applying to the fiber or by filling the same with a predetermined quantity of its natural or substitute oils, moisture, or both, to increase the strength and life and to improve the finish of the fiber, and to reduce the waste and fly, and to facilitate easier spinning from more pliable and elastic fibers, and to produce stronger and better finished articles manufactured therefrom.

Other objects and advantages will be made manifest in the following specification for an embodiment of the invention illustrated in the accompanying drawing, in which:—

Figure 1 is a longitudinal section of a drawing and doubling frame with the apparatus embodying our invention attached thereto.

Figure 2 is a fragmentary plan view of said frame.

In the drawing 1 indicates a standard drawing and doubling frame. Skeins of fiber such as cotton 2 are drawn out of containers 3 at one side of the frame 1 between drawing rollers 4 which compress the skeins flat at 5 and deliver the same into containers 6 at the other side of the frame.

Our invention includes a housing 10 which we mount upon the drawing and doubling frame 1, said housing being formed with a mixing chamber 11 at one end, an initial treating chamber 12 in communication with and adjacent said mixing chamber, a sump 13 at the bottom of said initial treating chamber, a final treating chamber 14, a sump

15 at the bottom of said final treating chamber, and a passage 16 connecting said initial treating chamber and said final treating chamber. The housing 10 is mounted on the frame 1 with the initial treating chamber 12 at the entrance side of rollers 4, the final treating chamber at the delivery side of said rollers, and the passage 16 extending from said initial treating chamber over said rollers to said final treating chamber. The initial treating chamber 12 is provided with an inlet 17, through which the skeins 2 are introduced into said chamber, and with an outlet 18 through which the skeins are passed out of the chamber and between the rollers 4. The final treating chamber 14 is provided with an inlet 19, through which the skeins 2 are passed from between the rollers 4 into the chamber, and with an outlet 20 through which the skeins are passed out of the chamber into the container 6. The mixing chamber 11 is provided with an inlet 21 in the top thereof through which is introduced an atomizer 22. A drain 23 is provided in the bottom of the mixing chamber 11. A drain 24 is provided in the sump 13. In the upper wall of the initial treating chamber 12 is a door 25. The sump 15 is provided with a drain 26. The final treating chamber 14 is provided with an outlet 27 which may be connected with the source of oil supply through which outlet the oil vapor may escape from said chamber after its final treatment of the skeins 2. A door 28 is provided in the top of the final treating chamber 14.

Natural fiber oil, or its substitute oil is atomized in the atomizer 22 and introduced into the mixing chamber 11, from which the oil passes in a fog or vapor form into the initial treating chamber 12 where it initially impregnates the skeins 2, then passes through passage 16 into the final treating chamber 14 in a highly concentrated condition where it finally, thoroughly and permanently impregnates the initially treated and flat rolled skeins 2, the remaining oil vapor passing out of the chamber through outlet 27 and back to its source of supply from which it is again used as above described.

We claim:—

1. In combination with a drawing and doubling frame, a housing formed with a mixing chamber, a treating chamber and communicating means between said chambers,

- the skeins of fiber, passing through the frame, being passed through said treating chamber, and means for introducing atomized oil-vapor into said mixing chamber.
5. 2. In combination with a drawing and doubling frame, a housing formed with a mixing chamber, an initial treating chamber, a final treating chamber, and a passage leading from said initial treating chamber to said final treating chamber, said initial treating chamber and said final treating chamber being so arranged that the fiber skeins pass first through the initial treating chamber, then through the drawing rollers of the frame, and then through the final treating chamber, and means for introducing atomized oil-vapor into said mixing chamber.
10. 3. In combination with a drawing and doubling frame, a housing formed with a mixing chamber, a treating chamber and communicating means between said chambers, the skeins of fiber, passing through the frame, being first passed through said treating chamber, and means for introducing
15. 4. In combination with a drawing and doubling frame, a housing formed with a mixing chamber, a treating chamber and communicating means between said chambers, the skeins of fiber, passing through the frame, being passed through said treating chamber, after passing between the drawing rollers of said frame, and means for introducing atomized oil-vapor into said mixing chamber.
20. 5. In combination with a drawing and doubling frame, a housing formed with a mixing chamber, a treating chamber and communicating means between said chambers, the skeins of fiber, passing through the frame, being passed through said treating chamber, means for introducing atomized oil-vapor into said mixing chamber, and a door in the top of said treating chamber.

In testimony whereof we hereunto affix our signatures.

CLARENCE C. SELDEN.
ROBERT D. PEARSON.
